CLAIM

The ornamental design of an electrical cord mount, as shown and described.

DESCRIPTION

FIG. 1 is a front elevation view of an electrical cord mount in accordance with the present design;

FIG. 2 is a front perspective view thereof;

FIG. 3 is a left side elevation view thereof;

FIG. 4 is an alternative front perspective view thereof;

FIG. 5 is a further alternative perspective view thereof;

FIG. 6 is a right side elevation view thereof; and,

FIG. 7 is a top plan view thereof.
